ORNAMENTAL EXPANDED METAL SHEET FOR BALCONY RAILS

Dallas S. Casley, Belpre, Ohio, assignor to Penn Metal
Company, Inc., Boston, Mass.

Filed Aug. 25, 1960, Ser. No. 61,891

Term of patent 14 years

(Cl. D54—2)

FIGURE 1 is a plan view of a section of an ornamental expanded metal sheet for balcony rails showing my new design.

FIGURE 2 is a sectional view taken on line 2—2 of FIGURE 1.

I claim:

The ornamental design for an expanded metal sheet for balcony rails, as shown.
